United States Patent

Des. 238,878

Patented Feb. 17, 1976

238,878

ELECTRICAL CONNECTOR

Guy Vernon Harkins, Harrisburg, Pa., assignor to
AMP Incorporated, Harrisburg, Pa.

Filed Mar. 21, 1975, Ser. No. 560,742

Term of patent 14 years

Int. Cl. D13—03

U.S. Cl. D26—1

FIG. 1 is a perspective view of an electrical connector showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and

FIG. 7 is a rear elevational view thereof.

I claim:

The ornamental design for an electrical connector, as shown.
